RACK FOR HOLDING SUGAR BAGS

Daniel Bloomfield, Chicago, Ill.

Application June 2, 1958, Serial No. 51,141

Term of patent 14 years

(Cl. D80—10)

Fig. 1 is a view in perspective of a rack for holding sugar bags embodying my new design.

Fig. 2 is an end elevational view thereof.

Fig. 3 is a side elevational view thereof.

Fig. 4 is a top plan view thereof.

Fig. 5 is a bottom plan view thereof.

I claim:

The ornamental design for a rack for holding sugar bags, substantially as shown.
